METHOD OF SETTING PRINTING INK

Albert E. Gessler, New York, N. Y., assignor to
 Interchemical Corporation, New York, N. Y.,
 a corporation of Ohio

Application July 26, 1940, Serial No. 347,659

4 Claims. (Cl. 101—416)

This invention relates to the art of printing, and has particular reference to a new and novel method of drying typographic or lithographic printing inks containing solvents which are substantially non-volatile at ordinary room temperatures, but which evaporate rapidly at elevated temperatures.

In my U. S. Patent No. 2,087,190, issued July 13, 1937, I first described a new type of printing ink containing a binder dissolved in a solvent substantially non-volatile at ordinary pressroom temperatures, but which evaporates rapidly at temperatures of the order of 150° C., and which made possible the high speed typographic printing of non-absorbent high quality paper stocks. This type of ink may be dried by passing the printed material through various types of high temperature heaters; a preferred method of drying employs gas heaters giving radiant heat of sufficient intensity to cause burning of the solvent vapors coming from the ink, as described in the Helmer U. S. Patent No. 2,127,956, issued August 23, 1938.

I have discovered an improved method of drying press-stable inks containing combustible solvents, by means of which the temperatures of the heaters may be substantially reduced for a solvent of any given volatility. My method comprises treating the printed material, after printing, with a rapidly volatile combustible liquid, and passing it through a simple open gas flame, whereby the added readily volatile liquid immediately ignites, and thus induces and aids in the evaporation and ignition of the solvent in the ink, reducing materially the amount of gas ordinarily needed to cause combustion or evaporation. Because the solvent and added liquid burns immediately adjacent the printed material, its heat is most effectively utilized, and lower operating temperatures are attained.

The low boiling liquid used should have a flash point so low that it ignites at ordinary room temperature, or slightly above room temperature. I have found that liquids with a flash point of 100° F. (open cup) or lower are satisfactory for use in my method.

Preferably, the added liquid is one which has no substantial solvent effect on the binder of the ink, and is miscible with the less volatile solvent. If such a volatile liquid is used, the volatile liquid, on admixture with the solvent of the ink, precipitates the binder and causes drying; the combustion of the liquid and solvent thereafter removes both the very volatile liquid and

the ink solvent, thus preventing resoftening of the ink.

The liquid may be applied by spraying, by a coating machine, by an intaglio cylinder, or by any other means. Preferably, it is somewhat thickened with a solute, in order to enable more even application.

The attached drawing shows diagrammatically a set up with which my invention may be practiced. The paper web 11 passes through a typographic printing unit 12 where an ink is applied, comprising pigment dispersed in a vehicle comprising a binder dissolved in a solvent substantially non-volatile at ordinary press room temperatures. The intaglio cylinder 13, cooperating with the impression cylinder 14, applies a coating of readily ignitable liquid to the sheet; it immediately goes into the combustion chamber 15, equipped with a row of burners 16, which ignites the solvent, the combustion continuing during the passage of the web through the chamber, and being substantially complete in the chamber. An exhaust vent 17 removes the products of combustion. The web is then passed over a cooling roller 18 to a rewind, or to another printing unit for printing another color or for printing the reverse side.

Typical examples of combinations which may be used to produce the desired effect are the following:

Example 1

An ink of the following composition is printed on a web of paper—

	Parts by weight
35 Dry $\frac{1}{2}$ second RS nitrocellulose.....	22.5
Butyl carbitol acetate (acetate of the mono- butyl ether of diethylene glycol).....	67.5
Gas carbon black.....	10.0

40 The printed web is then passed through a spray of 80% ethyl alcohol, and directly into a combustion unit where the alcohol is ignited, thus causing evaporation and ignition of the solvent of the ink.

Example 2

An ink consisting of—

	Parts by weight
50 Alkyd resin (glycerol phthalate, modified with 22% non-drying oil acids and 19% rosin).....	35.0
Butyl carbitol acetate.....	17.5
Petroleum distillate (boiling range 250— 290° C.).....	17.5
55 Barium lithol toner.....	30.0

was printed as in Example 1, and set by coating with isopropyl alcohol laid down from a gravure cylinder, followed by flashing of the alcohol and combustion of the vapors of the petroleum distillate. Preferably, the isopropyl alcohol is thickened by incorporating 1% of 5 second alcohol soluble nitrocellulose, or 1% of 1000 second ethyl cellulose.

Example 3

An ink consisting of—

	Parts by weight
Olefine—diolefine polymer resin	35.0
Petroleum distillate (boiling range 279— 334° C.)	25.0
Chrome orange pigment	45.0

is set by the use of isopropyl alcohol, as in Example 2.

Other inks containing combustible liquids may be used; and the solvent used for priming the combustion of the ink solvent may be any combustible solvent with a flash point of 100° F. or lower, whereby the ignition of the vapors is instantaneous on contact with a flame. The method may obviously be applied to typographic and lithographic printing, and to sheets or webs of paper, metal and other printable surfaces.

I claim:

1. The method of high speed printing which comprises applying to a surface a press-stable printing ink comprising a solution of a binder in a solvent substantially non-volatile at ordinary press room temperatures, thereafter applying to the printed surface a combustible liquid volatile at room temperatures, and passing the printed surface through a combustion chamber containing an open flame whereby the added liquid immediately ignites and the liquid and ink solvent are vaporized and the vapors burned.

2. The method of high speed printing which comprises applying to a surface a press-stable printing ink comprising a solution of a binder in a solvent substantially non-volatile at ordinary press room temperatures, thereafter applying to the printed surface a combustible liquid having a flash point below about 100° F., and passing the printed surface through a combustion chamber containing an open flame whereby the added liquid immediately ignites and the liquid and ink solvent are vaporized and the vapors burned.

3. The method of claim 2 in which the added liquid is thickened with a solute.

4. The method of claim 2 in which the added liquid is miscible with the ink solvent and is a non-solvent for the ink binder.

ALBERT E. GESSLER.
